United States Patent Office.

JOSEPH B. WILSON, OF PHILADELPHIA, PENNSYLVANIA.

Letters Patent No. 96,068, dated October 19, 1869.

IMPROVED WASHING-MACHINE.

The Schedule referred to in these Letters Patent and making part of the same.

I, JOSEPH B. WILSON, of Philadelphia, county of Philadelphia, State of Pennsylvania, have invented an Improved Washing-Machine, of which the following is a specification.

Nature and Object of the Invention.

My invention consists of a horizontal revolving wash-tub, combined with reciprocating beaters, and with certain devices which impart the required movements to the tub and beaters; also, of certain improvements in parts of the machine, whereby it is rendered more efficient in its operation, all of which is fully described hereafter.

Description of the Accompanying Drawing.

Figure 1 is a vertical section of my improved washing-machine.

Figure 2, a transverse vertical section.

Figure 3, a plan view.

Figure 4, a sectional plan on the line 1-2, fig. 1.

Figure 5, an enlarged view of the lower end of one of the beaters.

General Description.

To a horizontal board or platform, A, supported on suitable legs *a a*, are secured the posts B and B', connected together by the cross-bar D and board D', the whole constituting the stationary frame of the machine.

E is the driving-shaft, turning in suitable bearings on the opposite posts, B and B', and on this shaft are arms or projections, *d*, for actuating the beaters F, in the manner described hereafter.

On one end of the shaft is a suitable handle, *e*, and on the opposite end a bevelled pinion, *f*, gearing into a bevel-wheel, *h*, on a vertical shaft, G, which turns below in the platform A, and above in a projection on the frame.

The shaft G is provided with a pulley, *i*, round which and round the wash-tub H, or round a pulley attached to the same, passes a driving-band, *j*, a central pin, *k*, projecting from the bottom of the tub through the platform A, so that the said tub can revolve freely.

Each of the beaters F, above referred to, consists of a bar, arranged to slide freely in the cross-bar D and board D' of the frame, each bar being enlarged at the lower end *m*, and this enlargement is rounded on the under side, as shown in fig. 2.

I prefer to arm the lower ends of the beaters with strips, *n*, of gum-elastic, and also to screw to the bottom of the tub a sheet, *p*, of the same material, so as to prevent the possibility of any injury occurring to the clothes.

A pin, *q*, projects from each beater, and is within range of one of the arms *d* of the shaft E, so that on turning the shaft, the arm strikes the pin, elevates the beater, and, leaving the pin, permits the beater to fall by its own weight. The arms, however, are so ar-

ranged on the shaft that the whole of the beaters are not raised and permitted to fall simultaneously, but in succession.

The board D', above referred to, forms a part of the cover for the tub, as shown in fig. 2, the other portion, D'', of the cover being hinged to the board D', so that easy access may be had to the interior of the tub, after elevating the said portion D'' of the cover, the latter being situated so near to the edge of the tub as to prevent the splashing of the contents, but not too near to interfere with the free rotation of the same.

The tub having received the clothes to be washed, together with a suitable supply of water and soap-suds, the operator turns the handle *e*, and consequently operates the beaters, and at the same time turns the wash-tub, which may, by a proper proportioning of the bevel-wheels and pulley *i*, be so regulated, in respect to the movement of the beaters, that the lower ends of the latter will never strike the clothes at precisely the same place.

It will be seen that the enlarged ends of the beaters extend collectively entirely across the bottom of the tub, the space between the enlargements of the several beaters being sufficient only to permit them to clear each other. No portion of the clothes, therefore, is free from the blows of the beaters, if the operation of the machine be continued a short time.

A portion or portions of the clothes may certainly escape the action of a beater or beaters during one revolution of the tub. The portion thus escaping, however, will be elevated by the action of adjacent beaters, and the elevated portions will eventually be subjected to the action of one or more beaters, as the movement of the same and the tub is continued.

The consequence of all this is, that the water is forced through the interstices of the fabrics, and the latter thoroughly cleansed by beating action, and not by that rubbing and triturating effect, which is such a serious objection to ordinary washing-machines.

The beaters may be made entirely of wood, and may, if necessary, be weighted or depressed by suitable springs, but, for ordinary purposes, plain wooden beaters will suffice to produce the desired effect.

Claims.

1. A washing-machine, in which are combined, as described, the shaft E, vertical reciprocating beaters F, bevel-wheels *f* and *h*, shaft G, pulley *i*, and tube H, all operating as set forth.

2. The combination, with the tub and beaters, of a strip of elastic material, substantially as specified.

In testimony whereof, I have signed my name to this specification, in the presence of two subscribing witnesses.

JOSEPH B. WILSON.
